UNITED STATES PATENT OFFICE.

GEORGE S. EDWARDS, OF GREENCASTLE, PENNSYLVANIA.

DENTAL INSTRUMENT.

1,092,701.

Specification of Letters Patent.

Patented Apr. 7, 1914.

Application filed September 13, 1913. Serial No. 789,695.

To all whom it may concern:

Be it known that I, GEORGE S. EDWARDS, a citizen of the United States, residing at Greencastle, in the county of Franklin and State of Pennsylvania, have invented certain new and useful Improvements in Dental Instruments, of which the following is a specification, reference being had to the accompanying drawings.

This invention relates to new and useful improvements in dental instruments and more particularly to a tooth and root canal filler and the primary object of the invention is to provide a device of this character in which the filling material is constantly retained and which will permit a predetermined amount to be expelled therefrom.

A further object of the invention resides in providing a device which is simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawing forming a part of this application, Figure 1 is a side elevation of the device. Fig. 2 is a longitudinal section therethrough. Fig. 3 is an enlarged transverse section through the same as seen on line 3—3, Fig. 2. Fig. 4 is a similar view as seen on line 4—4, Fig. 2.

In describing my invention, I shall refer to the drawing in which similar reference characters designate corresponding parts throughout the several views and in which—

1 indicates a barrel, the one end of which has an arcuate tubular portion 2 secured thereto, the bore of said arcuate portion being of somewhat restricted diameter and suitably engaged with the free end of the arcuate portion 2, is a restricted tubular point 3 which forms the free and filling end of the device. A cap member 4 is provided and adapted for engagement with the outer end of the arcuate tubular member 2 to form a cap for the filling end of the device. The one end of the barrel 1, adjacent the arcuate member 2 is designed to form a chamber for filling material, as indicated at 5, and slidably mounted in said barrel, for the purpose of expelling the filling material from said chamber, is a plunger which consists of a

tubular member 6 and a removable solid end 7, the latter forming a head for the plunger and engaging the filling material in the chamber. The opposite or inner end of the tubular member 6 of the plunger is internally threaded, as shown at 8, and engaged with this threaded end, is a feed screw 9, the one end of which, disposed within said tubular member 6, is enlarged, as shown at 10 to form a stop for the feed screw. The opposite end of the feed screw 9 is suitably engaged with an enlarged head 11 which has a casing-like member 12 formed thereon to slidably receive the inner end of the barrel 1 therein.

Secured on the barrel 1, at a predetermined point thereon, is a tubular-like casing 13 which is enlarged at one end thereof to form a bowl-like head 14, the bottom of which has a pair of depressions 15 formed therein at substantially diametrically opposite points thereon. Mounted to rotate on the barrel 1, within the head member 14, is a disk 16, the same being secured to an enlarged head-like portion of a tubular member 17. This tubular member 17 is rotatably mounted on the barrel 1 and forms substantially a continuation of the tubular member 13 and a spring-forced pawl 18 is carried by the disk member 16 and adapted for engagement with the depressions in the base or bottom of the member 14, whereby to serve as an indicator to the operator. When turning the tubular portion 17, as will be described hereinafter, it will be understood that these stops, which are engagements of the pawls with the depressions, will be readily felt by the operator.

The free end of the casing-like member 12, formed on the head 11, has the bore thereof enlarged to receive therein the one end of the tubular member 17 and this end of the tubular member 17 is provided with a slot 19 which receives therein an inwardly extending lug 20 carried on the free end of the member 12. A collar 21 is secured on the barrel 1, to contact with the one end of the tubular member 17, whereby to prevent sliding movement of the latter on the barrel and said collar is also received in the enlarged end of the member 12. This collar also forms a stop to limit the outward movement of the member 12 with respect to the member 17. It will be seen from this construction that by turning the head member 11, the member 17 will be correspondingly

turned therewith, as will also be the disk-like member 16 carried by said member 17.

I have provided a means to prevent the rotation of the disk member 16 in one direction and, to this end, the peripheral edge of said disk member is offset or cut-away at predetermined points therein, as shown at 22, such offsetting providing a shoulder 23 and an inclined wall 24 at each cut-away portion. Arranged in each of these offsets to contact with the inclined wall 22 thereof, is a roller 25 and suitably mounted in the wall of each shoulder 23, is a spring-forced bolt 26, the head of the latter contacting 15 with the roller 25. The normal tendency of these spring-forced bolts 26, acting on the rollers 25, is to force said rollers outwardly in the offset portions 16 into contact with the inner peripheral wall of the head member 14. Thus, it will be seen that the disk 20 16 may be turned in one direction and the contact of said rollers against the inner peripheral wall of the member 14 will cause the spring-forced bolts to yield and permit 25 said disks 16 to be rotated, whereas when said disk is turned in the opposite direction, the rollers 25 will bind tightly between the inclined walls 24 and the inner peripheral wall of the member 14 and thus positively 30 prevent the rotation of said member 16. The purpose of providing such a construction for the prevention of the rotation of the member 16 in one direction, appears obvious.

35 In practice, the chamber 5 of the barrel 1 is filled with the filling material used by dentists and the device is retained in this condition until such time when it is desired to use the same. At such time, the cap member 4 is removed from the outer or filling end of the device and the operator, holding the device by the member 13, which is rigidly held on the barrel 1, turns the head member 11 so that the member 17 will be turned a 40 predetermined distance. This member 17 may be rotated a predetermined distance and this distance is calculated by the engagement of the pawl 18 with the notches or depressions 15 in the bottom of the member 14. By 45 this turning action, it is obvious that the feed screw 9 will be withdrawn from the tubular portion 6 of the plunger to a predetermined distance, it being understood that this tubular portion of the plunger will 50 be held stationary in the barrel 1, in view of the friction between the head member 7 and the inner wall of said barrel. By such turning action, the head member 11 is drawn outwardly, whereupon said head member, 55 with the plunger is then forced inwardly and with the inward forcing of the head member and plunger, a predetermined amount of filling material is expelled from the chamber 5, through the restricted end 60 of the device. This material may be forced 65

into the canal of the root of a tooth and when so done, the device may be set aside and kept in this condition until desired for further use.

From the foregoing description of the 70 construction of my improved device, the operation thereof will be readily understood and it will be seen that I have provided a device which is simple and durable in construction, inexpensive to manufacture and 75 one which will be very efficient and useful in operation.

While I have particularly described the elements best adapted to perform the functions set forth, it is obvious that various 80 changes in form, proportion and in the minor details of construction may be resorted to without departing from the spirit or sacrificing any of the principles of the 85 invention.

Having thus described this invention, what is claimed is:—

1. A dental instrument of the class described comprising a barrel, an arcuate tubular member connected to one end thereof and having a restricted bore, a plunger mounted for reciprocation in said barrel, a feed screw engaged with one end of said plunger and having a head on the outer end thereof adapted to contact with the opposite end of said barrel, and means in connection with the head on said feed screw and the barrel to limit the stroke of said plunger in the barrel. 90

2. In a dental instrument of the class described, a barrel, a tubular arcuate member connected to one end thereof and having a restricted bore, a plunger mounted for reciprocation in said barrel, a feed screw engaged with one end of said plunger within the barrel, a head carried on the outer end of said feed screw adapted for engagement with the opposite end of said barrel, and means in connection with the head of said feed screw 100 for calculating the adjustment of the latter and correspondingly limit the stroke of said 105 plunger.

3. In a dental instrument of the class described, a barrel, a tubular member of arcuate design having a restricted bore connected to one end of said barrel, a plunger reciprocally mounted in said barrel, a feed screw connected to said plunger and having a head on the outer end thereof adapted for engagement with the opposite end of said barrel, a member rotatably mounted on said barrel 110 and engaged with said head to rotate with the latter, said head member being so connected with said member as to move longitudinally of the latter, and means in connection with said rotatable member for calculating the adjustment of the feed screw. 115

4. In a dental instrument of the class described, a barrel, an arcuate tubular member connected to one end of said barrel and having a restricted bore, a plunger mounted for 120

reciprocation in the barrel, a feed screw engaged with said plunger, a head member mounted on the outer end of said feed screw adapted to contact with the opposite end of 5 said barrel, a bowl-shaped head member rigidly mounted on the barrel and having depressions in the base thereof, a member rotatably mounted on the barrel and having a portion thereof received in said head member, 10 a spring-held pawl carried by said rotatable member and adapted for engagement with the depressions in the base of said head member, and means for the engagement of said head member with said rotatable member 15 to cause the latter to be rotated with the former and simultaneously admit of longitudinal movement of the former with respect to the latter.

5. In a dental instrument, a barrel, an ar-
20 cuate tubular member connected to one end thereof and having a restricted bore, a plunger mounted for reciprocation in said barrel, a feed screw engaged with said plunger, a head member carried on the outer end of
25 said feed screw and adapted to engage the opposite end of said barrel, a tubular-like casing formed on said head member and re-

ceiving the last mentioned end of said barrel therein, the extreme free end of said tubular casing having the bore thereof slightly 30 enlarged, a member rotatably mounted on said barrel, and received in the enlarged bore of said casing, means connecting said casing with the rotatable member to cause the latter to be rotated with the former and 35 simultaneously permit longitudinal movement of the former with respect to the latter, a bowl-shaped member rigidly carried on said barrel and having depressions in the base thereof, said bowl-shaped member being 40 adapted to receive a portion of said rotatable member therein, a spring held pawl carried by said rotatable member and adapted to be received in the depressions of the bowl-shaped member, and means to prevent 45 the rotation of said rotatable member in one direction.

In testimony whereof I hereunto affix my signature in the presence of two witnesses.

GEORGE S. EDWARDS.
